(57) **CLAIM**

The ornamental design for a tilt housing of a downhole adjustable drilling inclination tool, as shown.

DESCRIPTION

FIG. 1 shows a rear elevation view of a tilt housing of a downhole adjustable drilling inclination tool showing my new design;

FIG. 2 shows a front elevation view thereof;

FIG. 3 shows a left side elevation view thereof;

FIG. 4 shows a right side elevation view thereof;

FIG. 5 shows a top plan view thereof;

FIG. 6 shows a bottom plan view thereof;

FIG. 7 shows a rear perspective view thereof;

FIG. 8 shows a front perspective view thereof; and,

FIG. 9 shows a reduced front perspective view thereof in an in use condition. The broken line showing of the downhole adjustable drilling inclination tool is for environmental purposes only and forms no part of the claimed design.

The broken line showing of various surface features on FIGS. 1-9 is included for the purpose of illustrating portions of the tilt housing of a downhole adjustable drilling inclination tool and forms no part of the claimed design.
